UNITED STATES PATENT OFFICE.

ABIJAH B. BENNETT, OF OPELIKA, ALABAMA.

BALING-PRESS.

1,002,213.

Specification of Letters Patent. Patented Sept. 5, 1911.

Application filed May 3, 1911. Serial No. 624,796.

To all whom it may concern:

Be it known that I, ABIJAH B. BENNETT, a citizen of the United States, residing at Opelika, in the county of Lee and State of Alabama, have invented certain new and useful Improvements in Baling-Presses, of which the following is a specification.

This invention relates to an improvement in baling presses for hay or similar material.

The invention relates more particularly to a press of this character which is power operated and one of the objects of the present invention is the provision of a simple and efficient mechanism for operating the press plunger by motive power.

A further object of the present invention is the provision in a press of this character of a baling chamber provided with improved means for preventing the withdrawal of any of the material in the baling chamber as the plunger is retracted.

A still further object of the invention is the provision of an improved construction at the discharge end of the baling chamber.

Further objects of the invention will be apparent from the detailed description hereinafter when read in connection with the accompanying drawings forming a part hereof, wherein a convenient embodiment of the invention is illustrated and wherein like numerals of reference refer to similar parts in the several views.

In the drawings:—Figure 1 is a side elevation of a baling press constructed in accordance with the present invention; Fig. 2 is a longitudinal section of the same, parts being shown in elevation. Fig. 3 is a top plan view of the baling press. Fig. 4 is a horizontal section thereof. Fig. 5 is a cross section on line 5—5 of Fig. 2. Fig. 6 is a cross section on line 6—6 of Fig. 2. Fig. 7 is a front elevation of the baling press, and Fig. 8 is a detailed view.

Referring now more particularly to the drawings, A A designate a pair of connected longitudinally extending sills which constitute the base of the press and from which extend upwardly a plurality of uprights B which serve to support the baling chamber C of the press.

The baling chamber C of the press comprises a top plate C' and a bottom plate C'', the outer ends of which project beyond the uprights at the outer ends of the supporting base of the press, and suitable side

plates C³ which are supported by the uprights extending from the base of the press. The top plate C' terminates short of the inner end of the baling chamber C so as to provide an opening through which the material may be fed into such baling chamber. The top and bottom plates of the baling chamber are secured in the frame in such a manner that the space between the same at their outer ends is slightly less than at their inner ends.

Pivottally connected to the uprights extending from the outer end of the supporting base of the press so as to form substantial continuations of the side walls of the baling chamber C, are outwardly extending gates D which coöperate with the projecting portions of the top and bottom plates of the baling chamber to provide a contracted discharge from said baling chamber. Means are provided for exerting pressure against the gates D to cause the same to frictionally engage the bale as it is moved from the baling chamber, such means being yieldable to permit of the discharge of the bale and the usual follower plates. In the present embodiment of the invention the means employed for this purpose comprises a U-shaped frame of metal E, the arms of which are adapted respectively to overlie the upper surface of the projecting portion of the top plate of the baling press and to underlie the undersurface of the bottom plate of the baling press. Loosely mounted upon the frame is a bar E' which is provided with suitable openings in the end portions thereof to engage the arms of the frame and which is adapted to lie against the base of said frame.

E² E² designate a pair of bars, each of which is provided with openings in the end portions thereof which loosely receive the arms of the frame E. The bars E² are adapted to lie one upon each side of the projecting portion of the baling chamber C and are provided on the inner sides thereof with inwardly projecting portions e which are adapted to engage the outer surfaces of the doors D.

Encircling the arms of the frame E and positioned between one of the bars E² and the bar E' are a pair of coil springs e'. Threaded upon the projecting ends of the arms of the frame E are hand wheels e².

From the above described construction it will be seen that by adjusting the hand

wheels e^2 the doors D may be moved inwardly to any desired extent and that at the same time they are free to yield in an outward direction as the bale passes therebetween. By reason of the formation of the inwardly projecting portions e on the inner surfaces of the bars E^2 , it will be seen that the doors D may be adjusted inwardly for a substantial distance beyond the planes 10 of the outer edges of the top and bottom plates of the baling chamber.

To prevent material in the baling chamber from working rearwardly therein, as the plunger is withdrawn, suitable stop 15 members are provided in the side walls C^3 of the baling chamber. In the present instance two such stop members are provided in each side wall of the baling chamber, said side walls being each provided 20 with a pair of longitudinally extending slots c extending therethrough in each of which is pivotally secured a stop member F. Each of the stop members F is angular in shape so as not to interfere with the inward movement of the plunger and is pivoted at its small end in one of the slots c , above referred to, so as to work freely therein. The outer edge of each of the 25 stops F is provided with a laterally extending portion f which is adapted to contact with the side wall of the baling chamber to limit the inward movement of the stop and to prevent the same from moving too far into the baling chamber.

30 Positioned upon the exterior of each of the side walls C^3 of the baling chamber C of the press is a vertically disposed leaf spring F', the ends of which lie upon the outer edges of the two stop members F which are supported by said side wall and tend to hold the same in a position projecting into the baling chamber of the press. The leaf spring F' is carried by a bar F² which may be adjusted longitudinally of 35 the side wall of the press. In the present embodiment of the invention, I have shown the bar F² as provided with a longitudinal slot f' which loosely engages a bolt f² which projects from the side wall of the baling chamber. A wing nut f³ threaded upon the outer end of the bolt f² serves to hold the bar F² in any position of adjustment. By 40 adjusting the bar F² it will be seen that the spring F' carried thereby will be also shifted so that the points of engagement of such spring with the stop members will also be shifted. By shifting the spring in this manner, it is possible to hold the stop members under any desired degree of tension.

45 In addition to the stop members F above described, I prefer to use at the upper portion of the inlet end of the baling chamber a tucker bar, the function of which is to prevent any material from working back 50 out of the baling chamber at this point.

The tucker just referred to comprises a bar G provided with a beveled lower edge and with extensions g extending from the ends thereof, which work in suitable guides g' formed in the frame of the press adjacent 70 the front ends of the top plate of the baling chamber. When the tucker is in its lowermost position, the lower edge thereof will be so positioned as to just permit the plunger to clear the same as it moves into the 75 operating chamber. Movement of the tucker bar in the guides g is resisted by a bowed leaf spring G' the ends of which rest directly upon the upper surface of said 80 tucker bar.

Secured to any suitable portion of the frame of the press and overlying the bowed spring G' is a bracket G² in which is threaded a screw G³ the lower end of which is adapted to engage the top of the bowed 85 spring G'. Obviously by adjusting the screw G³ just referred to the pressure exerted by the spring G' on the tucker block G may be regulated to any desired extent.

H designates a plunger which is adapted 90 to work within the baling chamber C. Extending rearwardly from the plunger H is a projection H' in which is journaled in any suitable manner, a roller H² which is adapted during the reciprocation of the 95 plunger to travel on the bottom plate C² of the baling chamber.

Extending upwardly from the inner end 100 of the base of the press and positioned between the side walls A A thereof is a standard I from the upper end of which extends two brace members I', the inner ends of which are rigidly connected in any suitable manner to the sides of the upright I and the forward ends of which are rigidly 105 connected to the front portion of the baling chamber of the press or to any other suitable portion of the frame thereof.

110 Journaled in suitable bearings carried by the sills A A is a shaft K to one end of which is secured a suitable driving pulley and to the other end of which is secured a balance wheel. Carried by the shaft K is a small pinion K³ which meshes with a larger pinion K⁴ which is mounted on a 115 stub shaft K⁵ journaled in a suitable bearing secured to one of the supporting sills A of the press.

L designates an elongated link one end of 120 which is loosely connected to a suitable crank projecting from the pinion K⁴ and the upper end of which is pivotally connected to the free end of a relatively short link L', the rear end of which is pivotally 125 connected to the upper end of the standard I.

M designates a pitman one end of which 130 is pivotally connected to the projection H' extending from the rear side of the plunger J and the other end of which is pivotally

connected to the link L below the point of connection between said link and the link L'.

When the plunger K is in its retracted position, the link L' projects upwardly from the standard I in a substantially vertical position. As the shaft K is rotated, however, the rotation of the larger pinion K⁴ will through the link L draw the link L' downwardly to a substantially horizontal position, and the pitman M will be shifted to cause the plunger to enter the baling chamber and compress the material which has been previously fed thereinto. By reason of the fact that the pitman M is connected to the link L below the point of connection of such link with the link L', it will be seen that a direct thrust is applied to the plunger during the operation of the device.

With power driven presses of this character difficulty has been experienced by reason of the breaking or straining of parts of the operating mechanism should the plunger be actuated when there is no charge in the baling chamber, and in the present invention I have sought to obviate this objection by providing means for preventing the operating mechanism from being subjected to any such strains even though it should be actuated when the baling chamber of the press is empty. In the present embodiment of the invention such means comprises a leaf spring N which is rigidly secured to the standard I and projects upwardly therefrom. The leaf spring N has rigidly secured to the upper end thereof a cross bar n to the extremities of which are pivotally connected the upper ends of a pair of downwardly extending links n'. Pivotally secured to the lower end of the links n' are a pair of links n², the free ends of which are pivotally connected to the link L'. The combined lengths of the links n' and n² is such that during the major portion of the downward movement of the link L' the spring N will not be brought into action. Just before the link L' reaches the limit of its downward movement, however, the links n' and n² will have been moved into alignment so as to form a direct connection between the link L' and the spring N. During the remainder of the downward movement of the link L' the spring N will be placed under tension so as to resist the movement of the plunger H during the extreme outer portion of its travel in the baling press.

From the above described construction it will be seen that the spring does not in any way interfere with the movement of the operating mechanism except during the extreme outer portion of the travel of the plunger when it is automatically brought into play to prevent any injury to the operating mechanism.

While I have illustrated a convenient embodiment of the invention in the drawings,

it will be obvious that many changes may be made to the form and construction therein shown without departing from the spirit and scope of the invention as defined in the appended claims.

70

I claim:—

1. In a device of the character described, a baling chamber comprising top, bottom and side walls, the top and bottom walls of said chamber projecting beyond the ends of the side walls thereof, doors hinged to the ends of said side walls and projecting outwardly therefrom, a U-shaped frame embracing the projecting portions of said top and bottom walls, bars loosely engaging the arms of said frame and positioned to overlie said doors, yieldable means interposed between one of said bars and the base of said frame, and adjustable means carried by the free ends of said frame and overlying the other of said bars.

75

2. In a device of the character described, a baling chamber, a stop member pivotally supported in one of the walls of said baling chamber, a resilient member engaging said stop member to normally project the same into the baling chamber, and means for adjusting said resilient member to vary its point of contact with said stop member.

90

3. In a device of the character described, a baling chamber, one of the walls of which is provided with a longitudinally extending slot therein, a stop member pivotally supported in the slot in the wall of the baling chamber, a leaf spring arranged to overlie the outer edge of said stop member, and means for adjusting said leaf spring to vary its point of contact with said stop member.

95

4. In a device of the character described, a baling chamber, one of the walls of which is provided with a pair of longitudinally extending slots therein, a stop member pivotally mounted in each of the slots in the wall of the baling chamber, a leaf spring adapted to overlie the outer edges of both of said stop members, and means for adjusting said leaf spring longitudinally of the wall of the baling chamber.

100

5. In a device of the character described, a baling chamber, one of the walls of which is provided with a pair of longitudinally extending slots therein, a stop member mounted in each of said slots, a member secured to the exterior of the wall of the baling chamber between said slots, means for adjusting said member longitudinally of the wall of the baling chamber, and a leaf spring carried by said member and adapted to overlie the outer edges of both of said stop members.

115

6. In a device of the character described, a supporting base, a baling chamber supported thereby, a plunger adapted to reciprocate in said baling chamber, a standard extending upwardly from said base in rear of

120

125

130

said baling chamber, a link pivotally connected to the upper end of said standard, a shaft rotatably supported on said base and positioned between said standard and the 5 baling chamber, a crank carried by said shaft, a link pivotally connecting said crank, and the outer end of the link pivoted to the standard, and a pitman pivotally connected at one end to said plunger and at its other 10 end to the link connected to said crank below its connection with the link connected to said standard.

7. In a device of the character described, a supporting frame, a baling chamber carried thereby, a plunger adapted to reciprocate in said baling chamber, a standard projecting upwardly from said supporting frame in front of said baling chamber, a toggle connection between the upper end of 15 said standard and said plunger, a crank shaft journaled in the frame between the baling chamber and said standard, a link connecting said crank shaft with one of the 20 links of said toggle, and means for driving said crank shaft.

8. In a device of the character described, a supporting frame, a baling chamber carried thereby, a plunger adapted to reciprocate in said baling chamber, a standard projecting upwardly from said supporting 25 frame in front of said baling chamber, a toggle connection between the upper end of said standard and said plunger, a crank shaft journaled in the frame between the baling chamber and said standard, a link connecting said crank shaft with one of the 30 links of said toggle, a spring interposed between one of the links of said toggle and the frame, and means for driving said crank 35 shaft.

9. In a device of the character described, a supporting frame, a baling chamber, a plunger adapted to reciprocate in said baling chamber, a standard extending upwardly from said supporting frame in front 40 of said baling chamber, a link pivotally connected at one end to the upper portion of said standard, a pitman connecting the free end of said standard and the plunger, means 45 for reciprocating said link, and a spring connection between said link and the frame.

10. In a device of the character described, a supporting frame, a baling chamber, a plunger adapted to reciprocate in said baling chamber, a standard extending upwardly from said supporting frame in front 50 of said baling chamber, a link pivotally connected at one end to the upper end of said

standard, a pitman connecting the free end of said link with said plunger, means for reciprocating said link, a leaf spring extending upwardly from the top of said standard, and a connection between said leaf spring and the link pivoted to said standard.

11. In a device of the character described, a supporting frame, a baling chamber carried thereby, a plunger adapted to reciprocate in said baling chamber, a standard extending upwardly from said supporting frame in front of said baling chamber, a link 60 pivotally connected at one end to the upper portion of said standard, a pitman connecting the free end of said link with said plunger, means for reciprocating said link, a leaf spring extending upwardly from the top of said standard, a link pivotally connected to said leaf spring, and extending downwardly therefrom, and a link pivotally connecting the lower end of said last mentioned link with the link pivoted to the 65 standard.

12. In a baling press, a baling chamber, a plunger adapted to reciprocate therein, means for reciprocating the plunger and resilient means for retarding the movement of the plunger during the extreme outer portion 75 of its stroke only.

13. In a baling press, a baling chamber, a plunger adapted to reciprocate therein, means for reciprocating the plunger, a 80 spring, a flexible connection between the plunger operating means and the spring, said flexible connection being of a length to become taut before the plunger is moved to its extreme outermost position.

14. In a baling press, a frame, a baling chamber, a plunger adapted to reciprocate therein, operating means for said plunger including a link pivoted to the frame, and a spring connection between said link and a 85 frame adapted to be brought into action after a predetermined amount of movement of said link.

15. In a baling press, a baling chamber, a plunger adapted to reciprocate therein, means for reciprocating the plunger, and means for cushioning the movement of the plunger during the extreme outer portion of its stroke only.

In testimony whereof I affix my signature 110 in presence of two witnesses.

ABIJAH B. BENNETT.
